UNITED STATES PATENT OFFICE.

EDWARD POSSON, OF CHICAGO, ILLINOIS.

GRAIN-DOOR.

1,067,548.

Specification of Letters Patent. Patented July 15, 1913.

Application filed September 20, 1910. Serial No. 582,894.

To all whom it may concern:

Be it known that I, EDWARD POSSON, a citizen of the United States, residing at Chicago, in the county of Cook and State of Illinois, have invented certain new and useful Improvements in Grain-Doors, of which the following is a specification.

The principal object of my invention is to provide a new and improved door for box 10 freight cars.

Another object of my invention is to provide a door for a box freight car that shall serve the purpose of an ordinary outside door and that shall at the same time be 15 adapted to close tightly so as to serve as a grain door.

Another object of my invention is to provide a sheet metal door for a box freight car that shall be rugged in use, and capable 20 of closing tightly to retain grain in the car.

Another object of my invention is to provide a tight closing door for a freight car with subsidiary openings through the door by which grain may be introduced or with- 25 drawn while the door itself remains in closed position.

Another object of my invention is to provide means for conveniently opening and closing a sliding door for a box freight car.

Still another object of my invention is to provide a door for a box freight car that shall be simple in construction, durable, 30 convenient to operate by unskilled workmen, and capable of closing tightly, so as to 35 retain grain in the car.

All these objects and various others will be made apparent in the following specification and claims, taken in connection with the accompanying drawings.

In order to disclose the principle of my invention I have shown a specific embodiment thereof in the accompanying drawings together with certain alternative modifications of details.

In these drawings—Figure 1 is a side elevation of a door constructed in accordance with my invention. Figs. 2 and 3 are horizontal sections on the lines 2 and 3 of Fig. 1. Fig. 4 is a perspective view of the door sill 45 and guide. Figs. 5 and 6 are sections thereof taken on the lines 5 and 6 of Fig. 4. Figs. 7, 8, 9 and 10 are sections on the respective lines 7, 8, 9 and 10 of Fig. 1. Figs. 11 and 12 are sections on the respective lines 50 55 11 and 12 of Fig. 10. Fig. 13 is an eleva-

tion on an enlarged scale of the lower right-hand corner of the door, as viewed in Fig. 1. Figs. 14 and 15 are sections on the respective lines 14 and 15 in Fig. 13. Fig. 16 is an elevation of a door embodying my invention, but modified in some respects as compared with that form of the invention disclosed in Figs. 1 to 15. Figs. 17 and 18 are vertical sections on the respective lines 17 and 18 in Fig. 16. Fig. 19 is an elevation on an enlarged scale of the lower right-hand portion of the door, as viewed in Fig. 16. Fig. 20 is a horizontal section on the line 20 in Fig. 16. Fig. 21 is a perspective view of a detail of Fig. 16. Figs. 22 and 23 are detail horizontal sections of a still further modified form in which my invention may be embodied.

Reference numeral 21 designates the side wall of a box freight car having the usual inside door opening which is closed by my 75 improved door 22. This door 22, as shown in Fig. 1, consists of sheet metal strengthened by the vertical and transverse ribs 28 which are struck out in it by a die. The top edge 41 of this door 22 lies within a top 80 guide comprising an inner plate 38 and an outer plate 25 spaced apart along their lower edges and both secured to the car wall under the eaves by means of the bolts 40. The sheet metal plate or flashing 39 85 laps over the guide plates 25 and 38 and under the fascia board 37, thus preventing water from running down inside of the door at its top.

The door sill is a plate 26, as shown in 90 Fig. 4, which lies on the wooden floor 34 and has its outer edge 26' upturned. The lower edge of the door 22 is designated 42 and this lies within the upturned lip 26'.

The member which constitutes the door 95 sill 26 extends with the section shown in Figs. 9, 11 and 12 clear across the lower part of the door opening and is then extended approximately an equal distance farther to the right of the door opening, the 100 section of this extended part being as shown in Fig. 6, that is, with a broad flange 26'' turned up and bolted to the side wall of the car. This part of the member 26 constitutes a channel with upstanding flanges 26' and 105 26'' and in the web of this channel is a series of equally spaced perforations 51, the purpose of which will be explained presently.

A plate 33 is riveted along the lower edge 110

of the door and laps down on the outside of the upstanding lip 26'; thus the lower edge of the door 22 rests on the plate-sill 26 and the upstanding lip 26', coacting with the edge 42 and the plate 33, afford guiding means for the lower edge of the door 22.

The door post 29 (from which the door 22 recedes when opened) is reinforced by the iron member 31 which has the horizontal section shown in Fig. 3. Its outer edge 31' is bent double, but spaced from the main part, so as to form a socket to receive the edge 48 of the door 22. The other side post 30 (the one past which the door moves when it is being opened or closed) is reinforced by the iron member 32 which has a backwardly turned outer edge 32'. The corresponding edge of the door 22 is formed as a hooked member 49 that engages the lip 32' when the door is closed, as shown in Fig. 3.

The upper part of the door 22 has a rectangular opening therethrough, the edges of which are struck outwardly, as indicated by the reference numeral 22" in Fig. 8. The edges 22" of this rectangular opening in the door 22 are reinforced by guide plates 64 above and 70 and 71 at the sides spaced out a little to receive the lateral edges 65 and 66 of the slide 23. The slide 23 is reinforced across its lower part by the angle iron 67. Below this is attached a housing 69 within which is pivoted a hooked dog 68 adapted to engage the lower edge 35 of the top-opening in the door 22 when the slide 23 is closed, as shown in Fig. 8.

The guide plate 33, at the lower edge of the door 22, is spaced out a little by means of the filler plate 43 and it projects up a little so as to form a guide for a sliding closure 24. This closure 24 comprises a sheet metal plate with two openings 22' therein. There are corresponding openings in the door 22 in its lower part with which these openings 22' are adapted to register. As viewed in Fig. 1, the sliding closure 24 is displaced to the right so that the openings are out of registry, but it will be obvious that by means of the handle 72 the sliding closure 24 can be shifted to the left, thus bringing the openings in registry. The guide lips 44 retain the upper edge of the sliding closure 24.

At the lower left-hand corner of the door 22, as viewed in Fig. 1, there is a reinforcing casting 45 whose construction and mode of application to the adjoining parts are made apparent in Figs. 10, 11 and 12. A toe 45' integral therewith hooks under the edge of the door sill 26.

At the lower right-hand corner of the door 22, as viewed in Fig. 1, a cast iron member or plate 57 is attached; this reinforces and strengthens the door, and carries an operating mechanism therefor. It also has

a lip 57' which extends under the edge of the door sill 26 similarly to the lip 45' on the casting 45.

The short shaft 52, journaled in the casting 57, carries a gear pinion 50, whose teeth engage the holes 51 in the extended channel part of the sill 26. The outer end of the shaft 52 has its sides flattened to receive a crank lever 53, the two parts being secured together by a transverse pivot pin 55. The shaft end of the crank lever 53 is beveled, as designated by the reference numeral 56, so that the handle end may be swung outwardly from the car. As shown in Figs. 13, 14 and 15, this handle end of the lever 53 is swung in toward the car. A hasp 54, pivoted on the staple 59, laps over the lever 53 and between the shoulders 58 on the casting 57. The upper end of this hasp 54 has an eye that engages the tongue 60, and a sliding dog 61 engages a hole in the tongue 60, so as to lock the hasp 54 in this position. The tongue 60 and the guide for the sliding tongue 61 are carried by a plate 63 riveted to one end of the sliding closure 24 and this same plate 63 carries a pivoted dog 62 which locks the sliding dog 61 in place.

A stop 27 is provided on the car wall 21 to prevent the door 22 from moving beyond a fully opened position.

Assuming that the door is fully closed, as in Fig. 1, and that the contents of the car consist of grain which it is desired to remove, the dog 62 will be swung aside, the sliding dog 61 raised, and the hasp 54 swung out and down. Then the operator will seize the handle 72 and move the sliding closure 24 to the left, so as to open the outlets in the lower part of the door 22. Thereupon, all the grain lying adjacent to the door 22 will run out through these outlets, thus relieving the door 22 from the pressure of the grain on its inner side. Then the operator will seize the handle end of the lever 53 and swing it out a little about the pivot pin 55. Next he will rotate this lever 53 in a clockwise direction which, by reason of the engagement of the gear pinion 50 with the recesses 51, will slide the whole door to the right. The remainder of the grain can then be removed from the car by the usual methods.

When it is desired to fill the car with grain, the dog 68 (Fig. 8) is unhooked, so as to permit the slide 23 to be lowered. Then the door 22 is closed and the sliding closure 24 at the bottom is also closed. The grain is introduced through the opening in the upper part of the door 22 and then the slide 23 is raised and the dog 68 automatically locks it in closed position, so that access can thereafter be gained to the interior of the car only by unlocking the hasp 54 at the bottom.

It will be observed that the lower edge of

the door 22 is definitely and positively guided on the sill 26 by means of the edge guide 42, the riveted lip 33, and the under-reaching hooks 45' and 57'. The upper guides 25 and 38 simply prevent the upper edge of the door from swinging in or out. The interlocking elements 48 and 31', and 49 and 32' (Fig. 3) come into engagement only when the door is closed and afford grain tight joints at the sides of the door. The disposition of the elements 33, 26' and 42 (Fig. 9) prevents the escape of grain at the bottom of the door.

The door 22 is simple and rugged in its mounting, no rollers or pulleys being employed. In opening and closing the door the principal friction to be overcome is along the sill 26 for the weight of the door rests on this sill. The door operating mechanism, shown in Figs. 13, 14 and 15, acts directly along the line of frictional resistance. By means of the handle 53 a powerful leverage is obtained, so that a workman can readily open or close the door and also force the interlocking edges 31', 48 and 32', 49 into close engagement or withdraw them therefrom.

Locking the hasp 54 not only locks the door as a whole, but also locks the sliding closure 24. When the upper slide 23 is closed it can be unlocked only from the inside.

The door posts 29 and 30 are reinforced by the members 31 and 32. These members also protect them against injury by abrasion of articles passing through the doorways or otherwise.

Referring now to the modifications shown in Figs. 16 to 21, in this case the door is a plane sheet of metal reinforced by the vertical edge angle irons 74 and 75 and the intermediate ones 77 and 78 joined across the top and bottom by other similar angle irons 76 and 79. These angle irons 76, 77 and 78 are spaced out a little from the door 73 by means of filler strips 81, 82 and 83, so as to afford guide channels for the edges of the slide 80 which is adapted to close the rectangular opening in the upper part of the door 73. This slide 80 has a reinforcing angle iron 84 across its lower edge to which are pivotally attached the ends of the bail 85 for which a locking device 86 is provided on the wall of the door 73. The casting 97 at the lower right-hand corner is similar to that shown in Figs. 13, 14 and 15, but the gear pinion 50 is on the lower side of the sill, here designated 96, and the rack 95 is riveted to the lower face of this sill 96 and is engaged by said gear pinion 50.

The general description of the mode of operation for the device of Figs. 1 to 15 inclusive will make clear the manner in which the device of Figs. 16 to 21 may be operated. The slide 80 can be raised or lowered

by means of the bail 85. The teeth of the rack 95 projecting downwardly do not become clogged with debris.

In Figs. 22 and 23 there are shown interlocking elements for the side edges of the door which may be built up instead of being formed integrally, as in Figs. 3 and 20. The member 31 has its edge 90, and a filler 91, and the flange 92 riveted together to receive the advancing edge of the door 73 when the door is closing. The following edge of the door has riveted thereto a filler 93 and flange 94 which engage the member 32 when the door closes.

It will be seen that I have constructed a simple and strong metal door which is adapted to perform the ordinary function of a side door for a freight car, which closes so tightly along its bottom and side edges that it will retain grain within the car, which engages the bottom and sides of the door opening so securely as to resist the outward thrust of grain within the car and which may be operated without difficulty by any unskilled workman.

I claim:

1. A box car having a door opening in the side wall thereof, in combination with an outer sliding door, a door sill having its outer edge turned up to form a track, said sill being extended to one side of the door opening and modified to form a rack, a gear pinion engaging said rack carried by the door, and a hand lever to rotate said gear pinion.

2. A box car having a door opening in the side wall thereof, in combination with a sliding outer door for said opening, a flat metal door sill having its outer edge turned up to form a track for the lower edge of the door, said sill and track being extended to one side to support and guide the door when opened, said extended part of the sill having a series of perforations to form a rack, a gear pinion carried by the door engaging said rack, and hand operated means to rotate said pinion.

3. A box car having a door opening in the side wall thereof, in combination with an outer sliding sheet metal door therefor, a flat metal door sill having its outer edge turned up, the lower edge of the door fitting inside of said turned up edge, and a cleat riveted to the lower edge of the door and extending down outside the turned up edge of the sill.

4. A box car having a door opening in the side wall thereof, in combination with an outer sliding sheet metal door therefor, a flat metal door sill having its outer edge turned up, the lower edge of the door fitting inside of said turned up edge, a cleat riveted to the lower edge of the door and extending down outside the turned up edge of the sill, said cleat projecting upwardly as well as down-

wardly, and a sheet metal sliding closure having its lower edge guided by the upper edge of said cleat.

5. A box car having a door opening in the side wall thereof, in combination with a sliding outer sheet metal door therefor, a flat metal door sill having its edge turned and engaged by the lower edge of the door, said door sill extending to one side of the door so as to support and guide the door in either opened or closed position, and members attached to the lower edge of the door and extending under the outer edge of said door sill.

15 6. A box car having a door opening in the side wall thereof, in combination with a sliding outer sheet metal door therefor, a flat metal door sill having its edge turned and engaged by the lower edge of the door, said door sill extending to one side of the door so as to support and guide the door in either opened or closed position, members attached to the lower edge of the door and extending under the outer edge of said door sill, and operating means mounted on the door and engaging said extended sill.

7. A box car having a door opening in the side wall thereof, a door sill extending to one side of the door opening to form a supporting and guiding track for the door when opened or closed, said extended part of the sill comprising a rack, an outer sliding door, a reinforcing member riveted to the lower part thereof, a gear pinion journaled in said reinforcing member and engaging said rack, and hand operated means to rotate said pinion.

8. A box car having a door opening in the side wall thereof, a door sill extending to one side of the door opening to form a supporting and guiding track for the door when opened or closed, said extended part of the sill comprising a rack, an outer sliding door, a reinforcing member riveted to the lower part thereof, a gear pinion journaled in said reinforcing member and engaging said rack, hand operated means to rotate said pinion, an opening through said main door, a subsidiary closure therefor, and interlocking elements carried partly by the main door and partly by the sliding closure and adapted when in engagement to also engage said hand operated means.

9. In a device of the class described, the

combination with a main door having means 55 to lock and unlock same on the outside, of a sub-door contained therein having a part of the main door lock fastening attached thereto, said part being held rigidly by the coacting parts when the main door is locked 60 and free to move with said sub-door when said main door is unlocked, the said main lock being operative only when both doors are closed.

10. A box car having a door opening in 65 its side, a door adapted to close said opening, a supporting and guiding track extending across the lower part of said opening and to one side thereof, said track comprising a rack, a gear pinion journaled on the 70 door and engaging said rack, and means carried by the door to be operated to rotate the gear pinion and thereby shift the door.

11. A box car having a door opening in 75 its side, a door adapted to close said opening, a supporting and guiding track extending along the lower part of said opening and to one side thereof, said track comprising a rack, means mounted on the door and engaging said rack, said means being adapted to be engaged manually so as to shift the door relatively to said rack.

12. A box car having a door opening in 80 its side, a door adapted to close said opening, a supporting and guiding track extending across the lower part of said opening and to one side thereof, mechanism mounted on the door and adapted to engage said track, and means adapted to operate said mechanism at a mechanical advantage so as 85 to shift the door relatively to the track.

13. A box car having a door opening in 90 its side, an outside door adapted to close said opening, a supporting and guiding track extending across the lower part of 95 said opening and to one side thereof, a guide for the top edge of the door, a rack comprised in said track, mechanism mounted on the door and adapted to engage the teeth of said rack, and means carried by the 100 door to operate such mechanism at a mechanical advantage so as to shift the door.

In testimony whereof, I have subscribed my name.

EDWARD POSSON.
